UNITED STATES PATENT OFFICE.

LOUIS N. D. WILLIAMS, OF OGONTZ, PENNSYLVANIA.

MACHINE FOR UNITING KNITTED WEBS.

1,315,064.

Specification of Letters Patent. Patented Sept. 2, 1919.

Application filed January 22, 1918. Serial No. 213,196.

To all whom it may concern:

Be it known that I, LOUIS N. D. WILLIAMS, a citizen of the United States, residing in Ogontz, Pennsylvania, have invented certain Improvements in Machines for Uniting Knitted Webs, of which the following is a specification.

My invention relates to a machine for uniting stitches constituting the terminal courses of two knitted webs, such for instance as the courses around the toe pocket and instep member of the foot web of a stocking. The objects of my invention are to render the machine substantially automatic in its action; to prevent waste of time in the operation of the machine, and to permit ready application and removal of the webs to be united.

In the accompanying drawing I have shown my invention as applied to a machine of the Keyser type, forming the subject of Letters Patent No. 1,069,336, dated August 5, 1913, but my invention is not limited in its application to machines of that type, the latter being selected simply for the purpose of reference.

In the drawing

Figure 1 is a top view of the machine, the sewing mechanism having been omitted in order to properly illustrate the parts below the same;

Fig. 2 is a rear view looking in the direction of the arrow *x*, Fig. 1;

Fig. 3 is a view partly in elevation and partly in transverse section, on the line 3—3, Fig. 1;

Fig. 4 is an end view of the machine looking in the direction of the arrow *y*, Fig. 1;

Fig. 5 is a top view partly in section and with some of the parts in different position from that illustrated in Fig. 1;

Fig. 6 is a similar view with the parts in still another position;

Fig. 6^a is an inner edge view of certain parts of the machine in the position shown in Fig. 1, but with the actuating pin at a more advanced stage of its movement than that shown in said figure.

Fig. 7 is a top view of certain parts of the machine not clearly shown in the other views, and

Fig. 8 is a side elevation of the mechanism for severing the stitch chain after the uniting of the webs has been effected.

In Fig. 2 of the drawing, 1 represents the fixed base of the machine, upon which is

mounted, so as to be free to rotate, a cylinder 2, the latter having at the base an outwardly projecting flange 4 upon whose periphery are formed ratchet teeth 5, as shown in Fig. 1, said ratchet teeth extending completely around the flange 4 except at the point 6 where a series of teeth have been removed. Within the cylinder 2 is properly mounted, so as to rotate therewith, a ring carrying 65 stitch-receiving points upon which are impaled the stitches of the terminal course of the two webs which are to be united. Such ring is shown by dotted lines at 2^a in Fig. 2 of the drawing, and the projecting stitch-receiving points thereon are shown at 2^b in said figure.

This web carrier is preferably of the type shown in Letters Patent 1,068,853, which provides for the transfer of single stitches 75 from the needles of the knitting machine to all of the points of the ring, and for then transferring the stitches from one half of said points to the other half so as to double the stitches upon the latter set of points, the 80 stitches to be united therefore extending only half way around the point ring.

The sewing mechanism of the machine may be similar to that of the Keyser patent, and need not therefore be herein described, 85 except in so far as to say that it comprises a needle 7 and a looper 8, one vibrating at a right angle to the other, and forming two rows of loops, those of one row being interlocked with those of the other row, and passing 90 through the webs so as to unite the same.

The mechanism for operating the needle and looper is driven by a shaft 9 which is free to turn in bearings in a U-shaped frame 10, mounted so as to be free to swing upon a 95 pivot pin 11 projecting upwardly from the base frame 1 of the machine, as shown in Fig. 2.

The shaft 9 can be operated directly from a belt pulley 12 through the medium of a 100 clutch comprising a radially projecting pin 13 on the shaft and a longitudinally projecting pin 14 on the pulley, or it can be driven indirectly, by hand, from a countershaft 15 mounted so as to be free to turn in a bearing 16 projecting rearwardly from the U-shaped frame 10, said shaft 15 being geared to the shaft 9 by means of intermeshing spur wheels 17 and 18, as shown in Fig. 1, and having, at one end, a hand wheel 19 in order to facilitate its manipulation.

It will, of course, be understood that when

the shaft 9 is being operated through the medium of the countershaft 15 the belt pulley 12 will be unclutched from said shaft 9 by moving it thereon so that the pin 13 is 5 beyond the path of travel of the pin 14, as shown in Fig. 1.

- 10 Intermittent movements of partial rotation are imparted to the cylinder 2 by a pawl 20 which engages the ratchet teeth 5 of the cylinder, and which is pivotally mounted upon the outer end of an arm 21 (see Figs. 1 and 2) said arm being pivotally mounted upon a stud 23 projecting from the base plate 1 of the machine, backward movement 15 of the pawl being effected by means of a spring 24 connected to the free end of the arm 21, as shown by dotted lines in Fig. 1, and forward movement being imparted to the pawl by means of an arm 25, Figs. 1 and 20 4, said arm 25 depending from a rocker head 26 which is free to turn on a shaft 27, the latter being secured to a supporting head 28, projecting forwardly from the U-shaped frame 10, as shown in Fig. 1.
- 25 The rocker head 26 has secured to it two inwardly projecting arms 30 and 31, each having at its rear end an anti-friction roller 32, that carried by the arm 30 being in position to be acted upon by a cam 33 on the 30 shaft 9, and that carried by the arm 31 being acted upon, at certain times in the operation of the machine, by a cam 34 carried by and rotating with the driving pulley 12, as shown in Fig. 1, the cam 34 having a longer 35 throw than the cam 33, as shown by dotted lines in Fig. 4.

Longitudinal movement of the belt pulley on the shaft 9, so as to carry the cam 34 alternately into and out of position to operate upon the anti-friction roller on the arm 31, is effected by means of a lever 35 pivotally mounted upon a projecting stud 36 on the frame 10, as shown in Fig. 2, and having on one arm a stud 37 engaging a 45 grooved collar 38 on the driving pulley structure, and on the other arm a pin 39 which is connected by a bar 40 to a lever 41, pivotally mounted upon an arm 42 which projects from the frame 10 and is by means 50 of a spring 42^a drawn toward the cylinder 2, until such movement is arrested by contact of a finger 42^b on the arm with a fixed stop on the base of the machine. The lever 41 is swung upon its pivot in the direction 55 of the arrow w, Fig. 1, by means of a coiled spring 43.

The inner arm of the lever 41 has upon it an upwardly projecting pin 44 with which co-operates the notched end of an arm 45 60 pivoted at 46 to a stud 47 on the base of the machine and acted upon by a spring 48 which tends to move it inwardly to the position shown in Fig. 5. Projecting upwardly from the base 4 of the cylinder 2 is a stud 50 whose upper end is beveled, as shown in Fig.

1, in which the stud is represented by two concentric circles, the larger and outer of which represents the diameter of the lower portion of the stud and the inner and smaller represents the diameter of the reduced upper end of the beveled top of the stud. The inner face of the arm 45 is beveled and on the top of the arm is a stop plate 51 whose forward face is also beveled and whose outer end also co-operates with the pin 44.

In first starting the machine, the lever 41 is adjusted to the position shown in Fig. 5, by operating the starting lever 35 by hand so as to move the driving pulley structure outwardly on the shaft 9 and bring the pin 14 into engagement with the pin 13 so as to drive said shaft 9 directly from the pulley 12. Previous to this time the pawl 20 operated in the blank space 6 of the cylinder flange, consequently the cylinder was without movement and the point ring with the webs upon it could therefore be readily adjusted to position in said cylinder. As soon, however, as the lever 41 was moved from the position shown in Fig. 1 to that shown in Fig. 5 it struck an upwardly projecting pin 51^a on the base of the cylinder and imparted a slight forward movement to said cylinder sufficient to carry in front of the pawl 20 the first ratchet tooth 5 in the rear of the blank space 6, and, as the pawl 20 is now being reciprocated by the cam 33 to an extent sufficient to carry it from one tooth 5 to the next, intermittent movements of partial rotation, each to the extent of one tooth, will be imparted to the cylinder 2, and the successive stitches of the webs will be presented to the sewing mechanism and will be united thereby.

This operation continues until the webs have been united throughout their extent, say for half a rotation of the cylinder 2, at which time the stud 50 comes into contact with the inner edge of the plate 51 and pushes the same and the arm 45 outwardly, so as to free the pin 44 on the lever 41 from engagement with the notch at the outer end of said arm 45, the lever 41 being then moved by the spring 43 so as to cause the pin 44 to come into contact with the outer end of the plate 51, as shown in Fig. 6, in which position the cam 34 acts upon the roller 32 on the arm 31 and rocks the structure 26 and pawl-actuating arm 25. On each stroke the pawl now engages a plurality of teeth 5, and the intermittent movements of the cylinder 2 are increased in extent until the full rotation of said cylinder has been completed and the pawl 20 is again resting in the blank space 6, whereupon further rotation of the cylinder is stopped so as to permit removal of the point carrier having the united webs thereon, and the replacing of the same by a point carrier having fresh webs upon it. The quick move-

130

ment of the cylinder 2 prior to the stoppage of the same provides more time for the changing of the web holders after such stoppage and before the machine is again started by movement of the lever 35. By the time the quick movements of the cylinder have been completed the beveled upper end of the stud 50 will have passed under the inner edge of the plate 51 and will have 5 lifted the same, as shown in Fig. 6^a, so as to carry its forward edge above the top of the pin 44 and thus permit the latter to move inwardly along the inner face of the arm 45, as shown in Figs. 1 and 6^a, this 10 movement permitting the lever 41 to so act upon the lever 35 as to move the cam 34 out of engagement with the anti-friction roller 32 and thus stop further movement of the rocking frame 26 and of the pawl-actuating arm 25 thereon.

If it is desired to place the operation of the machine under control of the counter-shaft 15, so as to provide for hand movement of any part at any time, the starting 25 lever 35 is moved to the position shown in Fig. 6, in which position the pulley 12 is inoperative for driving any part of the machine, the anti-friction roller 32 of the arm 31 being now in line with the concentric 30 collar 56 on said pulley structure, and consequently having no movement imparted to it. Adjustment of the starting lever so as to again move the pins 13 and 14 into engagement with one another causes movement 35 of the lever 41 to the position shown in Fig. 5, the arm 45 being then moved by its spring 48 into position to cause the notched end of the arm to again engage with the pin 44 and lock the lever 41 in the position 40 shown in Fig. 5.

After the uniting of the two webs has been completed the sewing mechanism of the machine operates for a short time longer in order to produce a chain of interlocked 45 loops around a finger 60 (Figs. 2 and 3) and in order to provide for severing the web-uniting stitches from the stitches on said finger 60 the sewing mechanism is moved away from the cylinder 2 by swinging the frame 10 upon its pivot stud 11, such action being effected by means of cams 61 and 62 50 on the outside of the cylinder 2, the cam 61 acting at the proper time on the toe 63 of an arm 64 projecting from the structure 55 10 and the cam 62 acting at a later period on a like toe 63 on an arm 65 on said structure 10, so as to swing the latter first in one direction to carry the sewing mechanism outwardly away from the cylinder and then in 60 the opposite direction to restore said sewing mechanism to operative position.

When the sewing mechanism is swung away from the cylinder 2 a line of stitches extends from the united webs to the finger 65 60 and is drawn between the jaws of a pair

of shears 66 mounted upon the outer face of the cylinder 2, as shown in Fig. 8. One of the shear jaws is fixed and the other movable, the latter jaw constituting one arm of a bell crank lever 67 which has a pin 68 70 entering a slot 69 in one arm of a bell crank lever 70 whose other arm has projecting and vertically separated pins 71 and 72, between which enters a cam plate 73 mounted upon that portion of the base structure which surrounds the flanged base of the cylinder 2, as 75 shown in Fig. 1.

The cam plate 73 has upon its upper face a cam 74 and upon its under face a similar cam 75, and, as the shear structure is carried 80 past said cam plate by the cylinder 2, the lower cam 75 will act upon the lower pin 72 of the lever 70 so as to close the jaws of the shears and sever the line of stitches between the united webs and the finger 60, and at a 85 further stage of movement of the cylinder 2 the upper cam 74 will act upon the pin 71 of the lever 70 to again open said shears.

The sewing mechanism should approach the web holder gradually in order to prevent 90 derangement of the needles in respect to the stitch-carrying points of said web holder which might result from sudden or abrupt approach, and for this reason the cams which act upon the lever arms 64 and 65 95 have beveled ends, as shown in Figs. 1 and 7.

In order to insure the retention of the fabric upon the impaling points 2^b during the sewing operation, a presser finger 76 is provided. Said finger is carried by an arm 100 77 pivotally mounted upon the structure 10 and, during the time the sewing operation is taking place, presses downwardly upon the fabric inside of the points 2^b, as shown in Figs. 1 and 2. When the sewing operation 105 is complete it is necessary that this finger 76 be raised so as to vertically clear the points 2^b and permit outward swinging movement of the structure 10. This raising of the presser finger is accomplished by means of 110 a cam 78 on the cylinder 2 which acts upon a toe 79 on the arm 77, so as to raise said arm at the proper time. Before the next sewing operation takes place, and after the frame 10 has been moved to restore the sewing 115 mechanism to operative position, the toe 79 is freed from the action of the cam 78, as shown in Fig. 2, and the finger 76 again bears upon the fabric inside of the impaling points 2^b.

It will be evident that modifications in the details of construction of the parts of the machine constituting the subject of my invention may be made without departing from the essential spirit of said invention as 125 set forth in the following claims.

I claim:

1. The combination, in a machine for uniting knitted webs, of a web carrier, sewing mechanism coöperating therewith to 130

- unite the knitted webs, means for moving the sewing mechanism from and toward the web carrier so as to cause a chain of stitches to bridge the space between the two, shears for cutting said chain of stitches, and means for operating said shears.
2. The combination, in a machine for uniting knitted webs, of a web carrier, sewing mechanism coöperating therewith to unite the knitted webs, means for moving the sewing mechanism from and toward the web carrier so as to cause a chain of stitches to bridge the space between the two, a finger for receiving and retaining said chain of 10 stitches, shears for cutting said chain of stitches between the webs and the needles, and means for operating said shears.
3. The combination, in a machine for uniting knitted webs, of a web carrier having stitch-impaling points thereon, sewing mechanism coöperating with said points to unite the stitches thereon, said sewing mechanism being movable from and toward the web carrier in order to carry the needle into 15 and out of operative relation therewith and being adapted to form a plurality of successive stitches when in inoperative position in respect to said web carrier, and means for causing gradual movement of said sewing mechanism toward the web carrier so as to prevent disarrangement of said sewing mechanism in respect to the stitch-carrying points as it is moved into operative relation thereto.
4. The combination, in a machine for uniting knitted webs, of a web carrier having ratchet teeth which extend around the same except as to a blank space at one point, a pawl for engaging said teeth, and 20 means for reciprocating said pawl, whereby the web carrier will be operated by a succession of intermittent movements for almost a complete rotation, and said movement will then be automatically arrested.
5. The combination, in a machine for uniting knitted webs, of a web carrier having ratchet teeth separated by a blank space, a pawl for acting on said ratchet teeth to move the web carrier by a succession of intermittent movements with an intervening period 25 when the pawl is engaging the blank space between the ratchet teeth, mechanism for starting the machine, a projecting stud on the web carrier, and a member of the starting mechanism bearing such relation to said stud when the latter is at rest that, in starting the machine, said member will contact with said stud and move the web carrier ahead far enough to bring the first tooth of

the ratchet into position to engage the driving pawl.

6. The combination, in a machine for uniting knitted webs, of a web carrier, means for operating the same, sewing mechanism for uniting the webs on said carrier and for forming a chain of free stitches after the webs have been united, and means for moving said sewing mechanism from and toward the web carrier so as to carry it into and out of operative relation with the webs thereon and cause the chain of free stitches to extend outwardly therefrom.

7. The combination, in a machine for uniting knitted webs, of a web carrier, means for operating the same, a starting device therefor, a stud on said web carrier, a locking arm for a member of said starting device, and a stop plate on said arm so disposed as to come within the path of the 70 stud on the web carrier and be raised thereby.

8. The combination, in a machine for uniting knitted webs, of a web carrier having ratchet teeth thereon, a pawl for engaging said ratchet teeth, and pawl operating means including two cams of different throw, and means for placing the pawl-operating device under control of either of these cams.

9. The combination, in a machine for uniting knitted webs, of a web carrier having ratchet teeth thereon, a pawl for engaging said ratchet teeth, and means for operating said pawl, said means including a 95 shaft with cam thereon, a driving device movable into and out of engagement with said shaft and having a cam with different throw from the cam on the shaft, a rocking device having two arms thereon, one for engaging the cam on the shaft and the other for engaging the cam on the driving device, and means whereby said rocking device is caused to act upon the pawl.

10. The combination, in a machine for 105 uniting knitted webs, of a web carrier, sewing mechanism coöperating therewith, shears for operating between said web carrier and said sewing mechanism, operating mechanism for said shears having a member with 110 vertically spaced points thereon, and a cam plate having upper and lower cams, one for acting upon the upper point and the other for acting upon the lower point.

In testimony whereof I have signed my 115 name to this specification.

LOUIS N. D. WILLIAMS.
